UNITED STATES PATENT OFFICE.

MARGARET B. SYLVA, OF CHICAGO, ILLINOIS.

HAIR WAVER.

Application filed March 27, 1928. Serial No. 265,038.

This invention relates to certain novel improvements in hair wavers and has for its principal object the provision of an improved construction of this character which will be 5 highly efficient in use and economical in manufacture.

The device as hereinafter described and claimed is an improvement over that shown in my Patent No. 1,577,598, issued on March 10 23, 1926.

The salient object of my invention is to provide a device adapted to operate in a manner substantially similar to that described in my above named patent and an 15 object ancillary to the foregoing is to provide a device of the foregoing character which may be expeditiously manufactured and placed in operating position.

Other objects will appear hereinafter. 20 The invention consists in the novel combination and arrangement of parts to be hereinafter described and claimed.

The invention will be best understood by reference to the accompanying drawings, 25 showing the preferred form of construction and in which:

Fig. 1 is a perspective view of a preferred embodiment of my invention;

Fig. 2 is a fragmental end view looking in 30 at the lowermost end of Fig. 1;

Fig. 3 is a sectional detail view depicting the device in operative position;

Fig. 4 is a view depicting a modified form 35 of construction for the end of the device opposite to that depicted in Fig. 2;

Fig. 5 is a sectional view taken substantially on the line 5—5 on Fig. 4; and

Fig. 6 is a fragmental view of a lock of 40 hair as it appears after having been waved by my improved device.

In the accompanying drawing wherein the preferred embodiment of my invention is illustrated, 10 indicates the main frame of my device which is substantially rectangular in formation so as to include parallelly extending side portions 11 and 12. The end 13 of the frame includes a portion which is inset a predetermined amount so as to define ears 14 and 15 at the corners of the frame. The end 16 of the frame includes an outwardly projecting portion 17 at substantially the mid-portion thereof.

A substantially U-shaped member 18 is provided and the bight portion 18^a thereof is 55 disposed so as to rest on the outer end of the portion 17 to which it is suitably secured.

The free ends of the limb portions 19 and 20 of the member 18 are suitably attached to the inset portion 21 of the bight portion 13 as illustrated in Fig. 1. This device 60 comprises the main frame of my improved waver.

In order that the frame will properly rest upon the scalp of the wearer, I form the limb portions 11, 19, 20 and 12 in such a 65 manner that they embody concavo-convex configuration in the longitudinal extent thereof.

Secured to the inset portion 21 substantially opposite the joining points of the limb 70 portions 19 and 20 are hook elements 22 and 23 which have the lowermost portions thereof disposed to be in alignment with the space between the limb portions 11 and 19 and 20 and 12. Mounted on the end 16 adjacent 75 the portion 17 so as to be pivotal thereabout are arms 24 and 25 which are disposed to extend below the inset portion 21 and these arms terminate in end portions 26 and 27. The arms 24 and 25 embody a 80 concavo-convex configuration longitudinally thereof which is of greater curvature than the concavo-convex formation of the limb portions 11, 19, 20, and 12 and this concavo-convex configuration terminates adjacent the 85 inset portion 21 such that when the portions 26 and 27 are disposed in the hook elements 22 and 23, the arms 24 and 25 will be securely locked in position.

In Fig. 3, the manner of using my improved waver is clearly illustrated and a lock of hair is indicated by 30. As is clearly illustrated therein, the ends of the lock of hair are directed under the limb portion 11 and are then directed around the arm 24 90 which at this time is preferably disengaged from the hook 22 and from the arm 24 the lock of hair is directed so as to extend below the limb portions 19 and 20 and it is then directed around the arm 25 which is preferably 95 disengaged at this time from the hook 23 and from the arm 25 the lock of hair 30 is directed under the limb portion 12. After this weaving operation is completed, the arms 24 and 25 are moved into 100 engagement with the hooks 21 and 22 and therefore since these arms embody a greater curvature than the limb portions 11, 19, 20, and 12, the arms 24 and 25 will be disposed 105 above the plane of said limb portions and 110 thus the hair will be drawn into a substantially taut condition. After the device has

been left positioned in the hair for a pre-determined length of time, it is removed and the hair will have assumed a wavy appearance substantially similar to that indicated in Fig. 6.

In Figs. 4 and 5 a modified form of construction is depicted and in this instance the main frame is constructed in substantially the same manner as that depicted in Figs. 10 1 and 2. However, in this instance in place 15 of the arms 24 and 25, a substantially U-shaped frame is provided which includes a bight portion 28 and limb portions 29 and 31. The limb portions 29 and 31 are formed substantially similar to the arms 24 and 25 and the ends thereof are adapted to be disposed so as to be directed below the inset portion 21. The bight portion 28 is adapted to rest on the upper side of the main frame in substantial alignment with the end portions adjacent the portion 17 and after the hair has been woven between the limb portions in the manner hereintofore set forth and when the hair is drawn taut, it is apparent that the hair will serve to hold the bight portion 28 and the limbs 29 and 30 in position. In Fig. 25 5 a sectional view of this construction is depicted and this relation is very clearly set forth in this view.

30 The foregoing clearly sets forth the preferred form of construction for my improved hair waver and it is apparent that this device may be formed from a rod-like material such as wire which may be expeditiously bent into the above described form and the adjoining portions of the wires may be expeditiously secured together as by soldering and it is therefore apparent that I have set forth a very economical construction which may be manufactured at a very 35 40 low cost.

While I have illustrated and described the preferred form of construction for car-

rying my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. In a device of the character stated, a frame member comprising side members and end members, bar members extending between said end members parallel to said side members, and other bar members hingedly connected to one of said end members intermediate said bar members and said side members, and means for detachably connecting the other ends of said last named bar members to the other of said end members.

2. In a device of the class described, a frame member comprising side members and end members, one of said end members including an outwardly offset portion at substantially the midpoint in the extent thereof, the other of said end members embodying outwardly offset portions at the junction thereof with said side members, said frame member having other bar members extending parallel to said side members from the central offset portion of said one end member to the other of said end members, and other bar members hingedly connected to said end member having said centrally located outwardly offset portion intermediate said offset portion and said side members, and means for detachably connecting said last named bar members to said other of said end members.

In testimony whereof I affix my signature.

MARGARET B. SYLVA.
